UNITED STATES PATENT OFFICE

90,869

DESIGN FOR A TUMBLER OR SIMILAR ARTICLE

Ira M. Clarke, New Martinsville, W. Va., assignor to The New Martinsville Glass Mfg. Co., New Martinsville, W. Va., a corporation of West Virginia

Application July 29, 1933. Serial No. 48,874

Term of patent 7 years

To all whom it may concern:

Be it known that I, IRA M. CLARKE, a citizen of the United States of America, and resident of New Martinsville, county of Wetzel, and State of West Virginia, have invented a new, original, and ornamental Design for a Tumbler or Similar Article, of which the following is a specification, reference being had to the accompanying drawing, in which—

The single figure is a perspective view of a tumbler or similar article, showing my new design.

The light lines of paneling discernible in the

drawing represent the outlines of substantially elliptical depressed panels present in the tumbler opposite or rearward of the similarly shaped and corresponding panels shown in full heavy lines on the front perspective, the same being thus visible and pictured due to light refraction on the tumbler when viewed in perspective.

I claim:—

The ornamental design for a tumbler or similar article, substantially as shown and described.

IRA M. CLARKE.
